(57) **CLAIM**

The ornamental design for a charger with washing apparatus, as shown and described.

DESCRIPTION

FIG. 1 is a perspective view of the front, right and top of a charger with washing apparatus;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is a cross sectional view at 8—8 in FIG. 2 thereof; and,

FIG. 9 is a reference view in the condition of the electrical shaver being placed in the charger with washing apparatus. The elements shown in broken lines are for illustrative purposes only and form no part of the claimed design.
